Howard Stevenson

UNITED STATES PATENT OFFICE

HENRY K. HARWICK, OF DARBY, PENNSYLVANIA

STEAM PIPE FOR LOCOMOTIVES

Application filed May 10, 1929. Serial No. 362,089.

My invention relates to certain improvements in the high pressure steam supply piping leading from the forward end of the boiler to the cylinder structures on the front 5 and rear frames of a simple "mallet" type locomotive.

One object of my invention is to provide supply pipes which extend from the smoke-box end of the locomotive to the cylinder 10 structure at the forward end of the rear frame of a simple "mallet" type locomotive. The piping arrangement, connecting the rear cylinder structure with the forward cylinder structure, forms the subject-matter of a separate 15 application filed by James C. Maris on the 10th day of May, 1929, under Serial No. 362,036, and I lay no claim to this particular part of the locomotive.

A further object of the invention is to dispense with the short slip joints which connect the boiler at the smoke-box end directly with the front cylinder structure in some 20 types of locomotives.

In the accompanying drawings:

25 Fig. 1 is a side view of sufficient of a high pressure simple "mallet" locomotive illustrating my invention;

Fig. 2 is a plan view; and

Fig. 3 is a sectional view on the line 3—3, 30 Fig. 1.

The drawings illustrate the forward end of a locomotive in outline, a number of the parts being omitted in order to more clearly illustrate my invention.

35 10 is the rear frame of the locomotive which supports the boiler 11. The forward end of the boiler overhangs the forward frame 12, which is connected to the rear frame by a link and universal coupling 13. 14 is a cylinder structure mounted on the forward end of the

40 rear frame, and 15 is a cylinder structure mounted on the forward end of the front frame. 16 is a dry pipe within the boiler of the locomotive and is coupled to a super-

45 heater header and throttle valve structure 17 in the smoke-box of the boiler. Leading from this throttle valve structure are two side pipes 18, which are connected by elbows 19 with the outside steam pipes 20, one at each side

50 of the boiler.

Each steam pipe 20 is coupled to a short pipe section 21, which in turn is coupled to a T section 22 through a slip joint 23. One branch 24 of each T joint 22 is coupled to the steam connection of the cylinder structure on that side of the locomotive. The other joint 25 is connected by a diagonal U-shaped branch pipe 26 to one branch of a Y-shaped chamber 27 formed in the saddle 28 of the cylinder structure 14. The two passages of 60 the Y, which connect with the two side steam pipes, unite in a single passage through which the live steam passes to the pipe 40 leading from the rear cylinder structure to the forward cylinder structure. 65

The pipe 40 is made in two sections 40^a and 40^b. The section 40^b is attached to a socket member of a ball-and-socket joint 29 which is rigidly secured to a cross-tie 30 extending from one side forward frame to the other. 70 The section 40^a is coupled to the rear cylinder structure by a ball-and-socket joint 31. In the present instance, the pipe section 40^a has a slip joint 32, and the pipe section 40^b extends into a slip joint 33 in the forward 75 cylinder structure 15. These two joints provide for a longitudinal movement of both sections of the steam pipe.

The rear cylinder structure 14 consists of a saddle 28 which is located between the side 80 members of the rear frame and the two cylinder castings 34 which are secured to the outside of said frame.

The forward cylinder structure is made substantially in the same manner, namely, a 85 centrally located saddle 37 and side cylinders, but it will be understood that the cylinders and saddle may be made integral without departing from the essential features of the invention. 90

The pipe 40 communicates with a Y-passage 36 in the forward saddle 37 of the forward cylinder structure, and pipes 38 lead from the passage 36 to the steam passages in the cylinder structures 39. 95

The exhaust steam from the rear cylinder structure passes through pipes 44 to the nozzle structure in the smoke-box, while the exhaust steam from the cylinder structure at the forward end of the front frame passes 100

through a pipe 42 to the nozzle, and in this latter pipe there is a slip joint 43.

The pipe 42 has the usual ball-and-socket joint at the cylinder structure and a ball-and-socket connection at the nozzle, to allow for lateral movement of the forward frame as well as a certain amount of vertical movement.

By the above construction all of the steam is conveyed from the steam pipes within the smoke-box of the boiler directly to the rear cylinder structure, where it is divided, a portion of the steam being directed to the valve chests of the rear cylinder structure, while the balance of the steam is conveyed through passages in the saddle of said structure to a pipe leading to the saddle of the cylinder structure at the forward end of the front frame, where it is divided, part going into the valve chests on one side of the cylinder structure, and the other part going into the valve chests on the opposite side thereof. This construction obviates the use of short pipes which in some instances are coupled directly to the forward cylinder structure of the locomotive and to the forward end of the boiler, and which must be so constructed as to allow the pipe to have considerable lateral and vertical movement.

30 I claim:

1. The combination in a high pressure simple "mallet" locomotive, of a front frame and a rear frame pivotally connected; a cylinder saddle on each frame; a cylinder secured to each side of each saddle; a live steam pipe extending from one cylinder saddle to the other; and two live steam pipes extending from the smoke-box end of the boiler to the cylinders on the rear frame, said pipe having an outside **T** coupling, one branch of the **T** being directly connected to the valve chest of a cylinder, the other branch of the **T** extending to the rear of the saddle and communicating with the pipe leading from the rear cylinder structure to the forward cylinder structure.

2. The combination in a high pressure simple "mallet" locomotive, of a rear frame; a front frame coupled to the rear frame; a cylinder saddle at the forward end of the rear frame; a cylinder secured to each side of said saddle; a saddle structure at the forward end of the front frame; a cylinder secured to each side of said saddle, each saddle having a **Y**-connection therein; a pipe connecting the **Y**-passages in the two saddles; and two steam pipes leading from the smoke-box end of the boiler to the rear cylinder structure, each of said pipes having an outside **T** section, one branch of each **T** being coupled directly to a valve chest of the rear cylinder, the other branch of each **T** being coupled by a **U**-shaped pipe to the rear end of the **Y**-passage in the saddle of the rear cylinder structure.

3. The combination in a high pressure simple "mallet" locomotive, of a front frame and

a rear frame; a cylinder structure on each frame; a live steam pipe extending from one cylinder structure to the other; and two live steam pipes extending from the smoke-box end of the boiler to the cylinder structure on the rear frame, each of said pipes having a **T** coupling, one branch of each **T** being connected to a valve chest of said rear cylinder; a diagonal **U**-shaped pipe coupling the other branch with a passage leading to the first-mentioned live steam pipe extending to the forward cylinder structure on the front frame.
